UNITED STATES PATENT OFFICE

2,475,084

THREAD ROLLING MACHINE

Alfred E. Drissner and William J. Hogg, Cleve-
land, Ohio, assignors to The National Acme
Company, Cleveland, Ohio, a corporation of
Ohio

Application April 29, 1944, Serial No. 533,432

18 Claims. (Cl. 80—6)

1

The present invention relates to thread rolling machines and has for its principal object the provision of an improved machine wherein the thread rolls are uniformly moved toward the work and rotated at a uniform speed.

Thread rolling machines on the market having shiftable rolls are more or less complicated and, in some of them, toggles and cams and numerous parts such as links, pins, etc., are used to control the movement of the thread rolls, resulting in inaccurate work, and none of the machines on the market, so far as I am aware, have proven very satisfactory in the production of accurate work and not accurate enough to produce a smooth, accurate Class 4 thread as demanded today by the Air Corps for aeroplane parts, whereas, the present improvement will not only meet the rigid Air Corps specifications and is not only simple in construction, but it is possible by means of this machine to roll threads with a tolerance of .0005 in the pitch diameter.

In the present improvement, therefore, an object of the invention is the provision of an improved machine whereby the thread rolls are all moved directly by a single rotary cam having a plurality of cam surfaces, one for each thread roll, thereby eliminating all linkages and intermediate parts.

A still further object of the invention is the provision of hydraulic operating mechanism for such machine which will accurately control the cam action on the cam slides.

A still further object of the present invention is the provision of mechanism hydraulically operated directly and uniformly to control the operation and speed of the rolls and which can be adjusted to suit requirements.

A still further object of the invention is simplicity of design and ease of operation together with positive action assuring extreme accuracy, not so far obtainable on other types of thread rolling machines, which will enable inexperienced operators to turn out very accurate work, something very important when quantity production is essential and skilled labor difficult to obtain.

In the drawings accompanying and forming a part of this specification, Fig. 1 is a diagrammatic lay out of the operating parts of the machine.

Fig. 2 is a front view of the machine.

Fig. 3 is a side view thereof.

Fig. 4 is a transverse vertical section taken on line 4—4 of Fig. 3.

Fig. 5 is a vertical section on line 5—5 of Fig. 2.

Fig. 6 is a sectional view similar to that shown

2

in Fig. 4 but showing more in detail the sliding thread rolls and their supporting mechanism.

Fig. 7 is a section on line 7—7 of Fig. 5 and illustrating the gear train.

Fig. 8 is a horizontal section on line 8—8 of Fig. 2.

Fig. 9 is a view of the driving mechanism from the fluid motor to the thread rolls.

Fig. 10 is a section on line 10 of Fig. 9, and Figs. 11 and 12 are views showing the movable support for the thread rolls.

Similar reference characters indicate corresponding parts in the several views.

Before explaining in detail the present improvement and its mode of operation, we desire to have it understood that the invention is not limited to the details of construction and arrangement of parts illustrated in the accompanying drawings since the invention is capable of other embodiments and that the phraseology employed is for the purpose of description and not of limitation.

For a general understanding of the present invention, reference may be had to Figs. 2 and 3 of the drawings showing the machine assembly and from which, also, its simplicity of construction may be noted.

The machine comprises the base 2 having suitably mounted thereon the head stock or gear box 3.

The base portion of the machine houses the hydraulic motor unit and oil reservoirs for both the hydraulic and cooling oils and the head stock or gear box 3 houses the movable parts controlling the rotation of the thread rolls and also the mechanism for controlling the inward and outward movement of the thread rolls.

As hereinbefore mentioned, within the base 2 (see Fig. 1) is the hydraulic unit and this unit comprises a motor 4 having at each end thereof the fluid pumps 5 and 6. A suitable fluid motor 7 is used for driving or rotating the tool or thread roll spindles 8 hereinafter to be described.

This fluid motor 7 is provided with a flow control valve 9 for controlling the speed of rotation of the thread rolls and this flow control valve 9 is flexible so as to control the speed where different speeds are required in working on different materials. A rotary control gauge 10 and release valve 11 are provided for the fluid motor 7.

This entire unit is independent of the unit used to control the operation of the cam for moving the thread rolls to and from the work.

The motor pump 6, of the same construction as the pump 5, is adapted to control the move-

ment of the cam, hereinafter described, for shifting the rolls to and from the work.

This shifting unit also comprises a flow control valve 13 similar in construction to the valve 9, which valve 13 is provided with a relief valve 14 and control gauge 15. From this control valve 13, the fluid passes into a solenoid four-way valve 16 and thence into the cylinder 17 for operating the piston 18, all of which will be further described in connection with the operation of the machine.

The stroke of the piston 18 is limited by a limit switch 19 which controls a time-delay valve 20 through stops 21. The switch is supported for movement with the piston rod 22 attached to the piston 18. These stops may be adjusted to limit the stroke of the piston as will be noted hereinafter.

For the convenience of the operator, the machine is provided with a foot-controlled switch 23 so that his hands will be free for loading pieces and feeding them into the machine. A hand control switch 24 is also provided.

As hereinbefore mentioned, in the head 3 of the machine is located the motor 1 adapted to rotate the shaft 24' and this motor and shaft are coupled together by means of the coupling 26 and keys 27. The motor 1 is also provided with a constant displacement fluid pump for controlling the rotary movement of the thread rolls and spindles.

On the shaft 24' is located a worm 28 secured for rotation therewith and adapted to engage a worm gear 29 splined to a shaft 30. On this shaft 30 is a gear 31 adapted to mesh with a similar gear 32 splined to a shaft 33 having secured for rotation therewith at its opposite end a gear 34. The gears 31 and 32 are adapted to be changed when desired, in order to change the speed of the spindles 8 beyond the limit of the fluid motor 1.

In the present instance, the gear 34 is surrounded by and meshes with three idler gears 35 mounted on appropriate stud shafts 35' in the housing (see Figs. 6 and 7). These idler gears are double-ended spur gears, the opposite ends of which are adapted to mesh with and drive the three spindle gears 36 secured to one end of the spindles 8 which carry on their opposite ends the thread rolls 38.

The ends of the spindles 8 carrying the tool or thread rolls are supported, in the present instance, in bronze bushings 61. However, suitable rolls, not shown, may be substituted for these bronze bushings 61 in order to take the pressure of the thread rolls.

Thus, it will be noted that the fluid motor 1 controls the speed of all three thread rolls uniformly and the present construction of spindle drive through the chain of gears referred to eliminates all flexible drives or complicated lever mechanism present in many machines. It will also be seen by reference to Fig. 7 that the idler gears 35 and spindle gears 36 are so located as to permit radial shifting of the tool or thread rolls and their spindles without materially affecting the correct meshing of the teeth of the gears 35 and 36, so that when the slides are moved in toward the work, as hereinafter described, the teeth of the gears will remain in mesh and these gears are so constructed that there is very little play between the teeth.

Where the motor 1 is of sufficient capacity, making it unnecessary to use the change gears 31 and 32, this motor can be mounted at right

angles to its present position in any suitable manner on the frame and a spur gear carried by the shaft 24' may directly engage the gear 32 on the shaft 33. In this construction, the worm 28 and worm gear 29, the shaft 30 and gear 31 would all be eliminated and a more direct drive obtained.

In order to shift the thread rolls 38 toward and from the work, a rotary cam 39 is provided having at its outer periphery, through 90 degrees thereof, teeth 40 adapted to engage the worm 41 carried for shiftable movement on the piston rod 22 attached to the piston 18.

The inner surface of this cam 39 is provided with three cam surfaces 42 adapted to engage rollers 43 carried toward the outer ends of the slides 44. These slides carry the roll spindles 8 which are adapted to be shifted toward the center when rolling a thread in a work piece. The slides are mounted in slide-ways 46 and are provided with a front support plate 45.

The cam 39 is adapted to rotate in the housing and is supported therein by rollers 47 engaging the outer periphery and these rollers are positioned in line with the slide rollers 43 to provide for easy sliding rotary movement of the cam 39. Actuation of the piston 18 will cause the worm 41 on the piston rod 22 to rotate the cam 39.

As hereinbefore mentioned, the piston rod has a predetermined stroke in accordance with the setting of the stops 21, thereby to rotate the cam disk 39 through any desired distance in order to shift the cam slides 44 the correct distance for rolling accurate threads.

The three roller slides, being operated in unison, will cause an even pressure on all three sides of the work and avoid crushing when it is desired to roll threads on hollow parts and also assures a perfect roundness of the thread.

Suitable springs 59 and plungers 60 urge the slides outwardly so that the rollers 43 will always bear against the cam surfaces 42 and these springs and plungers are effective to move the slides in an outward direction when the cam 39 is rotated in a reverse direction.

In machining the cam 39, the three cam surfaces 42, as before stated, are machined identically in order to give a uniform action and movement to the slides 44 so that the three thread rolls will exert an even pressure on the work.

In order to adjust the amount of movement of the thread rolls for obtaining a perfect pitch diameter on the work, a hand wheel 48 is provided to rotate the worm 41 thus changing the position of the cam 39 and, thereby, the position of the cam surfaces 42 relative to the rollers 43 and, therefore, adjusting the movement of the slides 44.

The construction of this machine thus permits the rolling of threads on a work piece to the exact diameter required and also permits rolling of threads on work of different diameters as long as the number of threads per inch and shape of threads are the same.

This machine may be adjusted to handle work from $\frac{1}{2}$ to $\frac{5}{8}$ " diameter simply by adjusting the position of the worm 41 through the wheel 48, as before explained. The stroke of the piston is controlled by the stops 21 and these stops are adjusted by means of adjusting rods 49 supported on the gear box and provided with adjusting screws 50 at opposite sides of the machine and adapted to engage switch toggle elements 51 of the limit switch 19 (see Fig. 8). This limit switch 75 19, in the present instance, is carried on a bracket

52 supported for movement with the piston rod 22.

When it is desired to roll fine threads, the stroke of the piston 18 can be reduced and time saved by not opening the thread rolls more than is absolutely necessary. To this end a stop screw 18' is threaded in the end of the cylinder, as illustrated in Fig. 8, to limit the stroke of the piston and piston rod 41.

When it is desired to change from one thread to another having a different pitch, it is only necessary to change the thread rolls 38 and adjust the flow control valves 9 and 13.

The work is carried in suitable work chucks and adapted to be fed into the machine in any suitable manner and, in the present instance, when the thread rolls contact the work, the work will freely rotate within the rolls. These roller chucks and feeding means have not been illustrated as they form no part of the present invention.

The base of the machine, as shown in Figs. 2 and 3, is also provided with the hydraulic oil valve gauge 53 for indicating the amount of oil in the reservoir and at the opposite side of the base an oil valve gauge 54 is provided to indicate the amount of cooling oil in its reservoir.

The head stock 3 which carries the operating mechanism for the thread rolls has on its face the support 55 for the rolls 41. The hand controlled switch 24 for starting and stopping the machine may also be carried by the head stock if desired. This head stock likewise carries the time delay valve 20 for controlling the time movement of the cam. Suitable strainers 56 and 57 for filtering the oil are provided, located in the base of the machine. The rotary control gauge 10 and cam control pressure gauge 15 are also located on the face of the head stock.

Suitable splash guards 58 are provided in front of the thread rolls.

In the operation of the machine, the proper thread rolls 38 are secured to the spindles 8 and the adjusting handle 48 set to control the position of the cam 39 for the desired pitch diameter of the threads to be rolled. The cam stops 21 are then set to limit the stroke of the piston for the desired movement of the cam slides 44. A piece of work is then fed to the machine and the motor started to rotate the threading rolls and the cam 39 to shift the slides 44 inwardly to roll the desired thread.

While this machine has been described as a thread rolling machine, by merely substituting the proper tools for this work, it may also be used for burnishing outside surfaces and for grooving parts where it is desired that the grooves be very accurate and smooth, or for other operations where three rolls can be applied with equal pressure on the work.

It is to be understood that, by describing in detail herein any particular form, structure or arrangement, it is not intended to limit the invention beyond the terms of the several claims or the requirements of the prior art.

Having thus explained the nature of our said invention and described a way of constructing and using the same, although without attempting to set forth all of the forms in which it may be made, or all of the modes of its use, we claim:

1. A rolling machine having a plurality of radially shiftable slides, rotatable spindles carried by said slides, tool rolls carried by said spindles, a rotary cam for uniformly shifting said slides, means including fluid controlled means and gear-

ing for actuating said cam, and independent means including fluid controlled means and gearing for rotating said tool roll spindles, the gearing for rotating the spindles comprising a gear carried by each tool spindle, a driving gear, a driven gear, a plurality of sets of driven spur gears, one of each set in mesh with the driven gear and the other in mesh with a spindle gear.

2. A rolling machine having a plurality of 10 radially shiftable slides, rotatable spindles carried by said slides, tool rolls carried by said spindles, a rotary cam for uniformly shifting said slides, means including fluid controlled means and gearing for actuating said cam, and 15 independent means including fluid controlled means and gearing for rotating said tool roll spindles, the gearing for rotating the spindles comprising a gear carried by each tool spindle, a driving gear, a driven gear, a plurality of sets of driven spur gears, one of each set in mesh with the driven gear and the other in mesh with a spindle gear, and the gearing for rotating the cam comprising teeth carried by said cam and a fluid actuated piston having teeth meshing with 20 said cam teeth.

3. A rolling machine having a plurality of 25 radially shiftable slides, rotatable spindles carried by said slides, tool rolls carried by said spindles, means for rotating said spindles, a rotary cam for uniformly shifting said slides toward and 30 from each other, a reciprocating piston for rotating the cam, and means for adjusting the stroke of the piston and comprising adjustable stops, a switch controlled by said stops, and means for adjusting the position of said stops.

4. A rolling machine having a plurality of 35 radially shiftable slides, rotatable spindles carried by said slides, tool rolls carried by said spindles, means for rotating said spindles, a rotary cam for uniformly shifting said slides toward and 40 from each other, a reciprocating piston for rotating the cam, and means for adjusting the stroke of the piston and comprising adjustable stops, a switch controlled by said stops, and 45 means for adjusting the position of said stops, said switch supported for movement with the piston.

5. A rolling machine having a plurality of 50 radially shiftable slides, rotatable spindles carried by said slides, tool rolls carried by said spindles, means for rotating said spindles, a rotary cam for uniformly shifting said slides toward and 55 from each other, a reciprocating piston for rotating the cam, and means for adjusting the stroke of the piston and comprising adjustable stops, a switch controlled by said stops, means for adjusting the position of said stops, and means for reducing the stroke of the piston.

6. A thread rolling machine having a plurality 60 of radially shiftable slides, rotatable spindles carried by said slides, tool rolls carried by said spindles, a rotary cam for uniformly shifting said slides, means for actuating said cam, and means for rotating the spindles and comprising a driving gear, a driven gear, a plurality of sets of driven spur gears, one of each set in mesh with the driven gear and the other in mesh with a gear carried by each tool spindle, and means for driving said driving gear.

7. A thread rolling machine having a plurality 65 of radially shiftable slides, rotatable spindles carried by said slides, tool rolls carried by said spindles, a rotary cam for uniformly shifting said slides, means for actuating said cam, and means 70 comprising fluid operated means for rotating the 75 comprising fluid operated means for rotating the

spindles and comprising a driving gear, a driven gear, a plurality of sets of driven spur gears, one of each set in mesh with the driven gear and the other in mesh with a gear carried by each tool spindle, and means for driving said driving gear.

8. A thread rolling machine having a plurality of radially shiftable slides, rotatable spindles carried by said slides, tool rolls carried by said spindles, a rotary cam for uniformly shifting said slides, means for actuating said cam, and means comprising fluid operated means for rotating the spindles and comprising a driving gear, a driven gear, a plurality of sets of driven spur gears, one of each set in mesh with the driven gear and the other in mesh with a gear carried by each tool spindle, and means for driving said driving gear, said gearing including change gears.

9. A thread rolling machine having a plurality of radially shiftable slides, rotatable spindles carried by said slides, thread rolls carried by said spindles, a rotary cam for uniformly shifting said slides, fluid controlled means for actuating said cam and including a reciprocating piston having worm teeth in engagement with similar teeth carried by the cam, means for adjusting the stroke of the piston, and means for rotating the thread roll spindles and comprising a driving gear, a driven gear, a plurality of sets of driven spur gears, one of each set in mesh with the driven gear, and the other in mesh with a gear carried by each thread roll spindle.

10. A rolling machine comprising a base and a gear box thereon, a hydraulic unit within said base, a hydraulic unit carried by said gear box, a plurality of radially shiftable slides, rotatable spindles carried by said slides, tool rolls carried by said spindles, a rotary cam for uniformly shifting said slides, all carried by said gear box, means controlled by said hydraulic unit within the base for actuating said rotary cam, and means controlled by said hydraulic unit carried by the gear box for rotating said tool roll spindles.

11. A rolling machine comprising a base and a gear box thereon, a hydraulic unit within said base, a hydraulic unit carried by said gear box, a plurality of radially shiftable slides, rotatable spindles carried by said slides, tool rolls carried by said spindles, a rotary cam for uniformly shifting said slides, all carried by said gear box, means controlled by said hydraulic unit within the base for actuating said rotary cam, means controlled by said hydraulic unit carried by the gear box for rotating said tool roll spindles, and means for adjusting the position of said cam.

12. A thread rolling machine having a plurality of radially shiftable slides, rotatable spindles carried by said slides, thread rolls carried by said spindles, a rotary cam for uniformly shifting said slides, fluid controlled means for actuating said cam and including a reciprocating piston having worm teeth in engagement with similar teeth carried by the cam, means for adjusting the stroke of the piston, means for rotating the thread roll spindles and comprising a driving gear, a driven gear, a plurality of sets of driven spur gears, one of each set in mesh with the driven gear and the other in mesh with a gear carried by each thread roll spindle, and adjustable means automatically operative for limiting the movement of said cam.

13. A thread rolling machine having a plurality of radially shiftable slides, rotatable spindles carried by said slides, threading rolls carried by said spindles, a rotary cam in direct engagement with said slides for uniformly shifting them, a hy-

draulic unit for oscillating said cam and embodying a reciprocating piston in direct engagement with said cam and fluid control valves for said cam, a hydraulic unit for rotating said thread roll spindles and embodying a fluid control valve for controlling the speed of the thread rolls.

14. A thread rolling machine having a plurality of radially shiftable slides, rotatable spindles carried by said slides, threading rolls carried by said spindles, a rotary cam in direct engagement with said slides for uniformly shifting them, a hydraulic unit for oscillating said cam and embodying a reciprocating piston in direct engagement with said cam and fluid control valves including a time delay valve for said cam, a hydraulic unit for rotating said thread roll spindles and embodying a fluid control valve for controlling the speed of the thread rolls.

15. A thread rolling machine having a plurality of radially shiftable slides, rotatable spindles carried by said slides, thread rolls carried by said spindles, a hydraulic unit for rotating said spindles and embodying means for controlling the speed of said spindles, a rotary cam for uniformly shifting said slides toward and from each other, a reciprocating piston for rotating said cam, a hydraulic unit for operating said piston, means for controlling the stroke of the piston and thereby the movement of the cam, and a time delay valve for said cam.

16. A thread rolling machine having a plurality of radially shiftable slides, rotatable spindles carried by said slides, threading rolls carried by said spindles, a rotary cam in direct engagement with said slides for uniformly shifting them, a hydraulic unit for oscillating said cam and embodying a reciprocating piston in direct engagement with said cam, a flow control valve for said cam in communication with a four-way valve located between said flow control valve and said piston, a time delay valve for said cam, and a hydraulic unit for rotating said thread roll spindles and likewise embodying a flow control valve for controlling the speed of the thread rolls.

17. A tool rolling machine having a plurality of radially shiftable slides, rotatable spindles carried by said slides, tool rolls carried by said spindles, a rotary cam for uniformly shifting said slides, fluid controlled means for actuating said cam and including a reciprocating piston having a rod with worm teeth in engagement with similar teeth carried by the cam, an adjusting member fastened to said piston to rotate the same and the worm teeth and thereby readjust the position of the rotary cam relative to the shiftable slides without longitudinally shifting the piston and the worm teeth, and means for rotating the tool roll spindles and comprising a driving gear, a driven gear, a plurality of sets of driven gears, one of each set in mesh with the driven gear, and the other in mesh with a gear carried by each thread roll spindle.

18. A thread rolling machine having a plurality of radially shiftable slides, rotatable spindles carried by said slides, thread rolls carried by said spindles, a hydraulic unit for rotating said spindles and embodying means for controlling the speed of said spindles, a rotary cam for uniformly shifting said slides toward and from each other, a reciprocating piston for rotating said cam, a hydraulic unit for operating said piston, means for controlling the stroke of the piston and thereby the movement of the cam, time valve means for said cam, said piston having a rod with worm teeth thereon engaging gear teeth on the rotary

cam, and an adjusting member fastened to said piston to rotate the same and thereby position the rotary cam relative to the slides.
